UNITED STATES PATENT OFFICE.

JAMES H. VAN DORN, DECEASED, LATE OF CLEVELAND, OHIO, BY MARGARET A. BAER,
EXECUTRIX, OF CLEVELAND, OHIO, ASSIGNOR TO THE VAN DORN IRON WORKS
COMPANY, OF CLEVELAND, OHIO, A CORPORATION OF OHIO.

MAIL-BOX.

1,202,251.

Specification of Letters Patent. Patented Oct. 24, 1916.

Application filed January 15, 1915. Serial No. 2,463.

To all whom it may concern:

Be it known that JAMES H. VAN DORN, late a citizen of the United States, and a resident of Cleveland, the county of Cuyahoga, and State of Ohio, now deceased, did during his lifetime invent certain new and useful Improvements in Mail-Boxes, of which the following is a full, clear, and exact description.

10 The object of this invention is to provide a strong and durable mail box of reasonable cost, which is substantially weather proof, and in which anyone may easily deposit letters, but from which only the authorized mail collector can remove them.

15 The invention consists in the construction and combination of parts shown in the drawing and hereinafter described and pointed out in the appended claims.

20 In the drawing Figure 1 is a front elevation of a letter box and support therefor embodying the invention; Fig. 2 is a side elevation of the same with the door open; Fig. 3 is a vertical section in the plane of line 3—3 on Fig. 1 of the upper part of the letter box when the letter-drop is open for the reception of letters; Fig. 4 is a similar section of the front part of the box when the letter-drop is closed; Fig. 5 is a sectional 25 plan through one side of the dome of the cap, the section being in the plane indicated by line 5—5 on Fig. 4; Fig. 6 is a vertical section in the plane of line 6—6 on Fig. 1; and Fig. 7 is a section to one side of the 30 letter box in plane 7—7 on Fig. 6.

35 Referring to the parts by letters, A represents the box body. This is preferably formed of sheet metal pieces, that is to say, a front wall a , a rear wall a^1 , two vertical sides a^2 , and a bottom a^3 , all of which parts are fitted and preferably welded together. The upper end of this box is open, and the 40 upper ends of the front and rear walls are curved toward each other, and the tops of the side walls are correspondingly curved, as shown in Fig. 2.

45 B represents the cap which is preferably made of cast iron. It is formed to fit and overlap the curved front and rear walls of the box, and to fit down upon the curved top of the side walls. This cap has a dome-like upward extension C, whose front wall is vertical; and through this front wall is a

rectangular opening c for the insertion of letters.

55 The letter drop E normally occupies the vertical position shown in Fig. 4, whereby it closes the rectangular opening in the front of the dome,—the top edge of said drop lying under and close to the upper edge of said rectangular opening. Across the front face of this letter drop,—that is the face which is the front face when the letter drop is in the closed position,—is a rib e having in its lower surface a cylindrical groove e' 60 which opens downward.

65 D represents the letter drop hinge bar. The foot d of this bar is secured, as by rivets, to the front face of the cap along the lower edge of the rectangular opening c ; and the 70 body of this bar extends upward, and has on its upper edge, a cylindrical rib d' which projects into and fits the cylindrical groove e' , whereby the letter drop is hinged to the cap in such position that it may swing from 75 one position to the other, as shown in Figs. 3 and 4. When the letter drop is in the horizontal position shown in Fig. 3, the letter may be inserted and laid upon the then horizontal letter drop. When, therefore, 80 the letter drop is allowed to turn to the position shown in Fig. 4, which it does by gravity, the letter will drop into the box. It is evident that when once the grooved rib e is hooked over the cylindrical rib d' , these 85 parts can not be disengaged except by the upward movement of the letter drop. When the letter drop is closed, such movement is 90 prevented because, as stated, the upper end of the letter drop lies beneath and close to the top wall of the opening which it closes.

95 Along both sides of this letter drop are the rearwardly projected flanges e^2 . The edges of these have the form of an arc, whose center is the axis of the hinge bar, and the radius of which is substantially the distance between this axis and the top wall of the letter drop opening. When, therefore, the letter drop is swung to the open horizontal 100 position shown in Fig. 3, these arc-shaped flanges will always have their upper edges close to and directly under the top wall of said rectangular opening, and thereby they 105 always prevent any upward movement of the letter drop. On each of these flanges is a shoulder e^3 , which are so placed that when

the letter drop is in open position they lie behind and close to the upper edge of said opening, and therefore they limit the swinging movement of said drop, and likewise prevent any outward movement of said letter drop such as might disengage it from said hinge bar.

In assembling the described parts, the rib d' is put into the groove e' before the hinged bar D is attached to the cap. Then when the letter drop has been passed through the rectangular opening c, and the hinged bar brought to the position shown, the latter is secured by rivets, as stated.

When this has been accomplished, the removal of the letter drop is impossible.

It is to be noted, that when the letter drop is closed the rib e overhangs the hinge bar rib and acts as a water shed to protect it from rain and snow. In order to effectually prevent rain or snow from getting into the letter box at the side of this letter drop, the side edges of the latter, above the hinge, are extended forward and then outward to form the flanges e^4 ; and in the rear face of each of said flanges is a vertical groove e^5 into which the side edges of the rectangular opening c project when the letter drop is closed, as shown in Fig. 5.

G represents a hollow pedestal having a base plate g, which may be fastened to the sidewalk. The upper end of this pedestal is rectangular, and fits nicely into the lower end of the letter box body. In order to furnish the recess for the reception of this pedestal, the bottom plate a^3 of the box body has a downwardly turned marginal flange a^4 , which flanged bottom plate fits and is secured in the lower end of the body. When the box is on the pedestal, these flanges go down over the top of the pedestal and the bottom plate rests on the top of the pedestal. This pedestal has two cross bars g', to which the bottom of the box is secured by the screws g'.

There is an opening a^6 in the front wall of the box for the removal of letters. This is normally closed by a door H which is hinged along its lower edge to that part of the front plate a which is adjacent to the lower edge of said opening a^6 . The box must, of course, be secured upon the pedestal while this door is open; because when the door is closed the screws are inaccessible.

This door has along its side edges the flanges h. These extend rearwardly into the box when this door is closed, or, rather more exactly, each extends into a pocket formed by one of the side walls and by an adjacent false side wall J which is secured to the sides of the box along its upper edge, as shown in Fig. 6. There is also an inclined false bottom K secured in the box, as shown in Fig. 6.

It is desirable that the door H be capable

of swinging so that when it is open it will be in a horizontal position, as shown in Fig. 6. To permit this an extension wing M is pivoted near its lower end to each of the flanges h. Each of these wings extends upward (when the door is open) alongside of the outer face of the associated flange, and it is provided with an outwardly turned finger m, which projects behind and is adapted to engage that part of the front plate a which forms the side wall of the door opening. Near the free end of each wing is an arc-shaped slot m', and into this projects a stop pin h' which is secured to the associated flange. When the door is swung open the fingers m engaging the front plate a will be stopped, but the door will be allowed to continue its swinging movement until the stop pins h' engage the ends of the slots m'. When the door is closed these extension wings, like the flanges h, will be in the pockets formed by the false sides J, and will, therefore, be out of contact with the letters. As the door is reaching its closed position the flanged edges of these extension wings will engage the bottom plate a^3 and will be stopped, but the door may continue to close because it can move relatively to these extension wings.

No attempt has been made to show the means by which this door is locked, since that is no part of the present invention, and any suitable locking device may be used for this purpose.

Having thus described the invention, what I claim is:

1. The combination with a letter box having a vertical front portion through which is a rectangular opening having horizontal top and bottom walls, and a hinge bar having a horizontal cylindrical rib along its upper edge which bar is formed independently of the box but is riveted thereto below and adjacent said rectangular opening, of a letter drop which is in the form of a flat plate whose width is slightly less than the width of said rectangular opening from side to side which letter drop is adapted to occupy a vertical position wholly within the letter box with its upper edge beneath and very close to the upper edge of said rectangular opening, said letter drop having on its front face an outwardly extended horizontal rib in whose lower face is a cylindrical groove which fits and is rotatable upon the cylindrical rib along the upper edge of the hinge bar, and said letter drop having along its side edges rearwardly extended flanges formed with arcual edges that always lie close to and beneath the upper edge of said rectangular opening.

2. The combination with a letter box, having a rectangular opening for the insertion of letters, of a letter drop, which, when

closed, is inside of said box and has its upper edge beneath and close to the upper edge of said rectangular opening,—said letter drop being provided on its front face 5 with a horizontal rib having in its lower surface a cylindrical groove, a hinge bar secured to said box adjacent to the lower edge of said opening and having along its upper edge a cylindrical hinge rib, which 10 projects into said groove, whereby the letter drop is hinged to said box, said letter drop having its side edges above the hinge extended forwardly and laterally to form flanges which lie in front of and outside of 15 the side edges of said rectangular opening, and said flanges having grooves in their rear faces which receive the side edges of said rectangular opening when the letter drop is closed.

20 3. The combination of a pedestal, and a letter box which fits upon said pedestal and

has downwardly extended flanges which embrace the top of the pedestal, said box having a bottom in which are holes for the 25 passage of screws; screws operable from inside of said box to connect the bottom of the box to said pedestal, said box having an opening in its front wall through which 30 said screws are accessible, and a door for closing said opening and a false bottom secured within said box inclined from its rear edge down to its front edge,—said false bottoms having holes through which a tool 35 may pass to operate said screws.

In testimony whereof, I hereunto affix my 35 signature in the presence of two witnesses.

MARGARET A. BAER,
*Executrix of the estate of James H. Van
Dorn.*
